UNITED STATES PATENT OFFICE

168,146

COMBINED HANDBAG AND UMBRELLA HOLDER OR SIMILAR ARTICLE

Julius de Kiszely, New York, N. Y.

Application June 28, 1952, Serial No. 20,407

Term of patent 3½ years

(Cl. D87—3)

To all whom it may concern:

Be it known that I, Julius de Kiszely, a citizen of the United States of America, residing in New York city, county of New York, and State of New York, have invented a new, original, and ornamental Design for a Combined Handbag and Umbrella Holder or Similar Article, of which the following is a specification, reference being had to the accompanying drawing, forming part thereof, wherein,

I claim:

The ornamental design for a combined handbag and umbrella holder or similar article, substantially as shown.

JULIUS DE KISZELY.
